SCOURING PAD HOLDERS

Georgina B. Clark, Feasterville, Pa.

Application March 30, 1953, Serial No. 345,390

6 Claims. (Cl. 15—209)

My invention relates to scouring pad holders, and it relates more particularly to holders which are flexible and capable of ready insertion and removal of the pad, as well as assurance of protection of all parts of the hand from contact with the pad.

One of the most efficient types of scouring pads is that which comprises steel wool. However, its use has proven dangerous to the user because fragments of steel wool become embedded in the hand which holds the pad. Attempts have been made in the past to provide auxiliary holding devices in order to protect the hand from contact with the pad. These have proven generally unsatisfactory however, for they were cumbersome, difficult and expensive to make, bulky, and substantially inflexible for guiding the pad about corners which are difficult to clean. Moreover in many instances, such attempts did not assure freedom from hand contact with the pad in all phases of its use including installation and removal of the pad from the holder.

One object of my invention therefore, is to provide a holder for a scouring pad, which shall be so constructed as to be readily flexed while permitting positive control of the pad in cleaning difficult corners.

Another object of my invention is to provide a holder for a scouring pad, which is so constructed as to permit ready disposal of the pad into fully covered condition when not in use, and facile projection of the pad into utile position, all without contact of the pad by the fingers.

A further object of my invention is to provide a holder for a scouring pad which is so constructed as to assure protection of the fingers from contact with the pad during the scouring operation.

Another object of my invention is to provide a holder for a scouring pad, which is readily and inexpensively manufactured, easily carried and which occupies a minimum of space when in use.

A further object of my invention is to provide a holder for a scouring pad, which is easily cleaned.

With the above and other objects in view, my invention consists of a holder for a scouring pad having a width, and a length; said holder comprising a flexible plastic sheet folded and sealed into a primary pocket portion having an entrance channel, and a base; and secondary pocket portions formed with their bases on either side of said entrance channel, and said secondary pocket portions extending along the outer face of said primary pocket portion and toward the base thereof; said entrance channel being shorter than the length of said base; said entrance channel being spaced from said base a distance greater than the length of said scouring pad, and said entrance channel being longer than the width of said scouring pad.

My invention also consists of a holder for a scouring pad, said holder being formed of a plastic sheet having a body portion comprising an upper edge and a lower edge, and lateral projections extending on either side of said body portion, said lateral projections each having an

2

upper edge portion and a lower edge portion; a fold disposed intermediate each of said lateral projections and said body portion; said upper edge portions of the body portion and of the lateral projections immediately adjacent each of said folds, being disposed substantially symmetrically about said fold; said lower edge portions of the body portion and of the lateral projection immediately adjacent each of said folds, being disposed substantially symmetrically about said fold; an edge of said body portion and the adjacent edge of one of said lateral projections being recessed at the fold therebetween; and the continuation of said last-mentioned body portion edge, and the adjacent edge of the other of said lateral projections being substantially similarly recessed at the fold therebetween, operably to render each of said folds shorter than the greatest distance between said upper and lower edges of said body portion; one of said lateral projections being folded about its adjacent fold until a face of said lateral projection is substantially juxtaposed to a face of said body portion; the other of said lateral projections being folded about its adjacent fold until a face of said last-mentioned lateral projection is substantially juxtaposed to said last-mentioned face of said body portion; and said body portion being itself folded about a fold extending from its said upper edge portion to its said lower edge portion, thereby dividing its opposed face into two segments and disposing said segments substantially in juxtaposition to each other; a juncture formed along said upper edge portions and between each of said lateral projections and said body portion, and between juxtaposed segments of said body portion; and a juncture formed along said lower edge portions and between said lateral projections and said body portion, and between said juxtaposed segments of said body portion.

My invention also consists of the parts and combinations of parts as more fully disclosed hereinafter.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized, and that my invention is not limited to the precise arrangements and organizations of the instrumentalities as herein shown and described.

Referring now to the drawings in which like reference characters indicate like parts:

Figure 1 represents a perspective view of a scouring pad holder embodying my invention.

Figure 2 represents a plan view of a blank which may be used in forming a scouring pad holder embodying my invention.

Figure 3 represents a perspective view showing one stage in the transfer of a scouring pad from a fully covered position in the holder, to an exposed position wherein it is ready for use, and embodying my invention.

Figure 4 represents a perspective view of a subsequent stage in the transfer of said scouring pad to a position wherein it is ready for use, and embodying my invention.

Figure 5 represents a perspective view showing a scouring pad holder in actual use in scouring a difficult corner, and embodying my invention.

Figure 6 represents a perspective view illustrating a method of returning the scouring pad from a position wherein it is ready for use, to a fully covered position, in a holder embodying my invention.

The scouring pad holder of my invention may be made of a blank 10 formed of a sheet of flexible plastic such for instance as vinyl, cellophane, or the like. In a preferred form, the plastic is transparent, although my in-

vention is capable of being made of a translucent or opaque (not shown) material. The blank 10 may comprise a body portion 11 having an upper edge or margin 12 and a lower edge or margin 13 which may be parallel thereto. A lateral projection 14 may be extended from one side portion 15 of the body portion 11, and is preferably formed integral therewith. A lateral projection 16 may be extended from the opposed side portion 17 and body portion 11, and is preferably formed integral therewith. A fold portion 18 is disposed intermediate the lateral projection 14 and the side portion 15, and preferably extends between the upper edge or margin 19 and lower edge or margin 20 of the lateral projection 14. A fold 21 may be disposed intermediate the lateral projection 16 and the side portion 17 of the body 10, and preferably extends between the upper edge or margin 22 and lower edge or margin 23 of the lateral projection 16. The upper margins 12 and 19 are preferably symmetrical about the axis 24 of the fold 18, and the lower margins 13 and 20 are preferably similarly symmetrical about said axis 24. The upper margins 12 and 22 are preferably symmetrical about the axis 25 of the fold 21 and the lower margins 13 and 23 are preferably similarly symmetrical about said axis 25. In a preferred form, the symmetrical and conjoint margins 12 and 19 are inclined toward each other as by angular or arcuate disposition with their apex 26 disposed substantially at the beginning of the fold 18. The margins 13 and 20 may be similarly disposed and with an apex 27 disposed at the opposed end of the fold 18. In this manner, the conjoint margins 12 and 19 form a recessed portion 28, and the conjoint margins 13 and 20 form a recessed portion 29. The conjoint margins 12 and 22 may be similarly disposed to form a recessed portion 30 with its apex 31 disposed substantially at one end of the fold 21 and the conjoint margins 13 and 23 may be likewise similarly recessed as at 32 with an apex 33 disposed substantially at the opposed end of the fold 21.

The outer end portion of the lateral projection 14 may comprise an edge 34 extending substantially between the margins 19 and 20. Similarly, the outer end portion of the lateral projection 16 may comprise the edge 35 extending substantially between the margins 22 and 23. The body portion 11 has a fold 36 extending between the margins 12 and 13, and preferably perpendicular thereto and intermediate the fold portions 18 and 21.

The blank 10 may then be folded about the fold 18, with the upper face 37 of the lateral projection 14 brought substantially into juxtaposition to the upper face 38 of the adjacent side 15 of the body portion 11. The lateral projection 16 similarly may be folded about the fold 21, with the upper face 39 of the lateral projection 16 being disposed substantially in juxtaposition to the upper face 40 of the side 17 of the body portion 11. The body portion 11 may itself be folded about the fold 36 so as to dispose the under faces 41 of the side segments 15 and 17 substantially in juxtaposition to each other. The blank 10 has thus been folded into position substantially as illustrated in Figure 1. It may then be sealed in said position by a plastic sealing device (not shown) whereby adjacent plastic elements are melted and united upon cooling. Thus, there may be formed a homogeneous mass 42 of plastic which has thus been molten and cooled, in the vicinity of the margins 13 and 20 and 23, and a similarly substantially homogeneous mass 43 may be formed along the opposed margins of the blank, said masses 42 and 43 extending substantially from the fold 36 to the folds 18 and 21. These substantially homogeneous masses comprise plastic seals, and it is to be understood that although a preferred form of my invention embodies the use of such seals, my invention is to be considered as not limited to such seals but may include as well other means of securing to each other juxtaposed sides and projections of the blank 10. Such other means may include sewing, riveting, stapling, cementing, or the like.

It will be found that there has thus been formed a primary pocket 44 extending from an entrance channel 45 to the base 46 disposed substantially along the fold 36; with secondary pockets 47 and 48 on either side of the entrance channel 45, and extending substantially from the seal 42 to the seal 43, and from their bases respectively formed along the folds 18 and 21 defining said entrance channel 45 of the primary pocket 44, to their own respective entrance channels, defined by the respective edges 34 and 35.

In operation, the holder 49 thus formed may be used in conjunction with a scouring pad 50 of any desired shape, but for the purposes of illustration, the pad 50 may be considered as having a width extending between its sides 51 and a length extending between its ends 52. The operator may embrace the holder 49 with his hand 53 by slipping his fingers 54 into one secondary pocket 48 and his thumb 55 into the other secondary pocket 47, with the base 46 of the pad 49 disposed substantially between the bases of the thumb 55 and the index finger 56. By spreading his thumb 55 apart from his fingers 54, he opens the entrance channel 44 of the pad 49 sufficiently to permit the entrance thereto of an end 52 of the scouring pad 50. The operator may then reach for said end 52 and embrace it with the side walls 41 of said entrance channel. Bearing against the pad 50 he may urge said side walls 41 about the pad 50 until a sufficient amount of the pad 50 has been inserted into the primary pocket 44 to enable the pad to be carried thereby. The operator may then withdraw his hand, and the holder 49 may then be lifted into upright position substantially as illustrated in Figure 6. By squeezing the opposed seals 42 and 43 toward each other in the vicinity of the entrance channel 45, the operator may widen the opening 35 of the channel 45 sufficiently to permit the pad 50 to drop the remainder of the way into the primary pocket 44 and substantially into abutting relation to the base 46. If desired, this transposition may be aided by gently shaking or vibrating the holder 49, or by a quick alternating of opening and closing movements comprising alternately pushing and pulling the entrance channel ends of the seals 42 and 43 toward and away from each other. The pad 50 is now safely ensconced in the holder 49.

When it is desired to use the pad 50, the base portion 46 of the holder 49 may be grasped between the thumb 55 and the fingers 54, and squeezed therebetween operably to cam the end 52 of the pad outwardly toward the entrance channel 45, substantially as illustrated in Figure 3. The thumb 55 and finger 54 may then be advanced toward the entrance channel and again moved toward each other in a manner to squeeze the holder 49 therebetween operably to cam the base 52 further toward the entrance channel 45, until a sufficient quantity of scouring pad has been projected outwardly through the entrance channel 45 to provide adequate scouring material for the operation at hand.

The operator then slips his fingers 54 into the secondary pocket 48 and his thumb 55 into the secondary pocket 47 and grasps the pad 50 through the flexible plastic walls of the primary pocket 44, substantially as is illustrated in Figure 5. In this position, the pad 50 may be urged into any desired corner as for instance the corner 57 of the utensil 58, or may be used for scouring any other surface. The recesses 28 and 30 and the recesses 29 and 32 combine to form an obtuse angle with the folds 18 and 21 which form the margins of the entrance channel 45, said obtuse angle reducing to a minimum, interference by the holder 49 with the pad 50 in the scouring operation, particularly when scouring in difficult corners. When the scouring operation has been completed, the pad 50 may be returned to its completely covered position in the holder 49 in substantially the same manner described hereinabove and as illustrated in Figure 6.

In the scouring operation, as well as in the loading,

pad-advancing and pad-receding operations, the flexible, impervious material of which the holder is made enables the operator freely to maneuver the pad in virtually all respects as though he were holding it directly and without the intervention of a holder, yet without danger of harm from contact with the pad itself. When it is desired to clean the holder, the pad 50 may be fully advanced out of the pocket 44, and then held under running water as under an open faucet (not shown). Each pocket 44, 47 and 48 in turn may thus be held momentarily under the stream of water. The action of the water is to dislodge any dirt, soap, grease or particles of steel wool and to carry it off with the flushing stream. No rubbing or wiping is necessary.

It will be noted that at no time in any of the foregoing operations is there any need for the operator to touch the scouring pad with his hands, and his use thereof is completely safe.

Moreover, the construction of the holder is such as to enable it to be folded or otherwise packaged or carried in a minimum of space and with a minimum of weight, as well as to be manufactured of inexpensive materials and with a minimum of operations, requiring merely a simple blanking, folding and one-stroke sealing operation.

I am aware that the invention may be embodied in other specific forms without departing from the spirit of essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new and desire to secure by Letters Patent is:

1. A holder for a scouring pad having a width and a length; said holder comprising a flexible plastic sheet folded and sealed into a primary pocket portion having an entrance channel and a base portion; and secondary pocket portions formed with their bases on each side of said entrance channel, and said secondary pocket portions extending along the outer face of said primary pocket portion and toward the base thereof; said entrance channel being shorter than the length of said base; said entrance channel being spaced from said base a distance greater than the length of said scouring pad, and said entrance channel being longer than the width of said scouring pad.

2. A holder for a scouring pad having a width and a length; said holder comprising a flexible plastic sheet folded and sealed into a primary pocket portion having an entrance channel and a base portion; and secondary pocket portions formed with their bases on each side of said entrance channel, and said secondary pocket portions extending along the outer face of said primary pocket portion and toward the base thereof; said entrance channel being spaced from said base a distance greater than the length of said scouring pad, and said entrance channel being longer than the width of said scouring pad.

3. A holder for a scouring pad; said holder comprising a flexible plastic sheet folded and sealed into a primary pocket portion having an entrance channel and a base portion; and secondary pocket portions formed with their bases on each side of said entrance channel, and said secondary pocket portions extending along the outer face of said primary pocket portion and toward the base thereof; said entrance channel being shorter than the length of said base.

4. A holder for a scouring pad, said holder being formed of a flexible plastic sheet having a body portion comprising an upper edge and a lower edge, and lateral projection portions extending on each side of said body portion, said lateral projection portions each having an upper edge portion and a lower edge portion; a fold disposed intermediate each of said lateral projection portions and said body portion; said upper edge portions of the

body portion and of the lateral projection portions immediately adjacent each of said folds, being disposed substantially symmetrically about said fold; said lower edge portions of the body portion and of the lateral projection portions immediately adjacent each of said folds, being disposed substantially symmetrically about said fold; an edge of said body portion and the adjacent edge of one of said lateral projection portions being recessed at the fold therebetween; and the continuation of said last-mentioned body portion edge, and the adjacent edge of the other of said lateral projection portions being substantially similarly recessed at the fold therebetween, operably to render each of said folds shorter than the greatest distance between said upper and lower edges of said body portion; one of said lateral projection portions being folded about its adjacent fold with a face of said lateral projection portion being substantially juxtaposed to a face of said adjacent body portion; the other of said lateral projection portions being folded about its adjacent fold with a face of said last-mentioned lateral projection portion being substantially juxtaposed to a face of its adjacent body portion; and said body portion being itself folded about a fold extending from its said upper edge portion to its said lower edge portion, said last-mentioned fold dividing its opposed face into two segments, said segments being disposed substantially in juxtaposition to each other; a juncture formed along said upper edge portions and between each of said lateral projection portions and said body portion, and between juxtaposed segments of said body portion; and a juncture formed along said lower edge portions and between said lateral projection portions and said body portion, and between said juxtaposed segments of said body portion.

5. A holder for a scouring pad, said holder being formed of a flexible plastic sheet having a body portion comprising an upper edge and a lower edge, and lateral projection portions extending on each side of said body portion, said lateral projection portions each having an upper edge portion and a lower edge portion; a fold disposed intermediate each of said lateral projection portions and said body portion; said upper edge portions of the body portion and of the lateral projection portions immediately adjacent each of said folds, being disposed substantially symmetrically about said fold; said lower edge portions of the body portion and of the lateral projection portion immediately adjacent each of said folds, being disposed substantially symmetrically about said fold; one of said lateral projection portions being folded about its adjacent fold with a face of said lateral projection portion substantially juxtaposed to a face of said body portion; the other of said lateral projection portions being folded about its adjacent fold with a face of said last-mentioned lateral projection portion being substantially juxtaposed to a face of said body portion; and said body portion being itself folded about a fold extending from its said upper edge portion to its said lower edge portion, said last-mentioned portion dividing its opposed face into two segments, said segments being disposed substantially in juxtaposition to each other; said two first-mentioned folds each being shorter than said body fold; a juncture formed along said upper edge portions and between each of said lateral projection portions and said body portion, and between juxtaposed segments of said body portion; and a juncture formed along said lower edge portions and between said lateral projection portions and said body portion, and between said juxtaposed segments of said body portion.

6. A holder for a scouring pad, said holder being formed of a flexible plastic sheet having a body portion comprising an upper edge and a lower edge, and lateral projection portions extending on each side of said body portion, said lateral projection portions each having an upper edge portion and a lower edge portion; a fold disposed intermediate each of said lateral projection portions and said body portion; said upper edge portions of the body portion and of the lateral projection portions immediately adja-

cent each of said folds, being disposed substantially symmetrically about said fold; said lower edge portions of the body portion and of the lateral projection portion immediately adjacent each of said folds, being disposed substantially symmetrically about said fold; one of said lateral projection portions being folded about its adjacent fold with a face of said lateral projection portion being substantially juxtaposed to a face of said body portion; the other of said lateral projection portions being folded about its adjacent fold with a face of said last-mentioned lateral projection portion being substantially juxtaposed to a face of said body portion; and said body portion being

itself folded about a fold extending from its said upper edge portion to its said lower edge portion, thereby dividing its opposed face into two segments and disposing said segments substantially in juxtaposition to each other.
